J. F. HEMENWAY.
CLOTHES WRINGER.
APPLICATION FILED OCT. 2, 1916.

1,226,331.

Patented May 15, 1917.

UNITED STATES PATENT OFFICE.

JOHN F. HEMENWAY, OF NEW YORK, N. Y.

CLOTHES-WRINGER.

1,226,331.

Specification of Letters Patent. Patented May 15, 1917.

Application filed October 2, 1916. Serial No. 123,376.

To all whom it may concern:

Be it known that I, JOHN F. HEMENWAY, a citizen of the United States, residing at New York city, in the county of New York 5 and State of New York, have invented certain new and useful Improvements in Clothes-Wringers, of which the following is a specification, reference being had therein to the accompanying drawing.

- 10 This invention relates to certain new and useful improvements in clothes wringers, and more particularly to means for limiting the upward movement for the movably mounted top bar used in connection with 15 pressure releasing devices, the object being to provide means for preventing the movably mounted top bar from jumping out of the wringer frame when the pressure is released.
- 20 Another object of my invention is to provide a movably mounted top bar with an outwardly extending member coöperating with a stop in such a manner that the top bar is free to move a predetermined distance 25 within the wringer frame so as to release the pressure but is prevented from moving entirely out of the frame.

Other and further objects and advantages of the invention will be hereinafter set forth 30 and the novel features thereof defined by the appended claims.

In the drawings,

Figure 1 is a side elevation of the upper portion of a clothes wringer partly in section showing the application of my improved construction of stop thereto;

Fig. 2 is a perspective view of the end portion of the movably mounted top bar showing the preferred form of extension.

40 Fig. 3 is a perspective view of the extension and stop detached from the wringer;

Fig. 4 is a detail perspective view of another form of stop;

Fig. 5 is a detail perspective view of another form of stop; and

Fig. 6 is a perspective view of still another form of stop.

Like numerals of reference refer to like parts in the several figures of the drawing.

50 In the drawing, 1 indicates the wringer frame which is provided with the usual pressure rolls and pressure means for said rolls, the pressure means being engaged by pressure screws 2 carried by a movably mounted 55 top bar 3 which is held in position within the wringer frame by a releasing mechanism

4 herein shown, constructed substantially the same as shown in my application filed September 9, 1916, Serial No. 119,177.

The pressure screws 2 carried by the movably mounted top bar 3 are mounted in threaded boxes 5 secured to the under side of the top bar as clearly shown, said boxes being provided with extensions 6 working in slots 7 of plates 8 carried by the end bars 1 of the wringer frame, said plates forming stops for the extensions so as to limit the upward movement of the movably mounted top bar when the pressure releasing means 4 has been moved out of the path thereof.

In the form shown in Fig. 4, the movably mounted top bar 9 carries a screw 10 extending laterally therefrom which is adapted to engage a screw 11 carried by the side bars 1 of the wringer frame so as to limit the upward movement of the top bar.

In the form shown in Fig. 5 the movably mounted top bar 12 carries a screw 13 which extends through a slot 14 carried by an angle plate 15 secured to the side bar 1 so as to allow the movably mounted top bar to move vertically within the wringer frame a predetermined distance in order to release the pressure means.

In the form shown in Fig. 6, the movably mounted top bar 16 is provided with a screw 17 working in the slot 18 formed in the plate 19 secured over the side bar as clearly shown for limiting the upward movement of the top bar.

From the foregoing description, it will be seen that I have provided in connection with a clothes wringer having a pressure releasing device, a top bar having an extension which coöperates with a stop for limiting the upward movement of the top bar in order to prevent the top bar from becoming detached from the wringer frame when the pressure is released.

I claim:

1. A clothes wringer, comprising a frame having pressure rolls and pressure means for said rolls, a movably mounted top bar having means for adjusting said pressure means, a releasing mechanism for said top bar, a member extending outwardly from said top bar in a plane below the top thereof, and a stop carried by the side bars of said frame coöperating with said extension for limiting the upward movement of said top bar.

2. A clothes wringer, comprising a frame

having pressure rolls and pressure means for said rolls, a movable top bar mounted in said frame, mechanism for holding said top bar in predetermined position therein, 5 boxes carried by said top bar provided with extensions, pressure screws mounted in said boxes for adjusting said pressure means, and plates carried by the side bars having slots to receive said extensions for limiting the 10 upward movement of said top bar.

3. A clothes wringer, comprising a frame having pressure rolls and pressure means for said rolls, a top bar movably mounted in said frame having means for adjusting

said pressure means, means for holding said top bar in predetermined position within said frame, a slotted plate secured to the side bar of said frame in a plane below the upper ends thereof, and a member extending outwardly from said top bar working in the 20 slot of said plate for limiting the upward movement of said top bar.

In testimony whereof I hereunto affix my signature in the presence of two witnesses.

JOHN F. HEMENWAY.

Witnesses:

GEORGE W. BEHRENS,
G. R. PATCHEN.
